COMBINATION BARRICADE AND WARNER

Harold W. Edgar, Williamsville, N.Y.

Application October 13, 1958, Serial No. 52,953

Term of patent 14 years

(Cl. D72—1)

Fig. 1.

Fig. 2.

Fig. 3.

Fig. 4.

Fig. 5.

Fig. 1 is a front perspective view of a combination barricade and warner, showing my new design;

Fig. 2 is a rear perspective view thereof;

Fig. 3 is an end elevational view thereof;

Fig. 4 is an opposite end elevational view thereof; and

Fig. 5 is a bottom plan view thereof.

The phantom lettering is for illustrative purposes only.

I claim:

The ornamental design for a combination barricade and warner, substantially as shown and described.
